VEHICLE JACK

Tom C. White, Billings, Mont.

Application January 23, 1935, Serial No. 3,097

5 Claims. (Cl. 254—133)

The present invention is primarily directed to an improved vehicle jack-head of the general type illustrated in my copending application, Ser. No. 732,813, filed June 25, 1934, now Patent Number 2,000,503.

Generally speaking, the invention pertains to a self-centering head for vehicle jacks which enables the operator to place the jack beneath any convenient part of the automobile, such as an axle, spring, etc., with the assurance that the head will be properly centered and will support the weight of the vehicle when the lifting rod of the jack is elevated. The improved head may be formed as a standard part of the vehicle jack or it may be readily applied in place of the conventional head, whether of the screw-threaded, ratchet rod, or hydraulic type.

A further object of this invention is to so construct a platform or base member, upon which the weight of the car rests in elevated position, that all of the weight is distributed directly over the elevating rod of the jack, thus relieving the head member from strain.

Referring to the drawing, Fig. 1 is a top plan view of the self-centering head and platform.

Figs. 2, 3, and 4 are vertical cross-sectional views taken on line 2—2 of Fig. 1.

Fig. 5 is a side elevation of the head.

Fig. 6 is a vertical cross-sectional view of a modified form of head and platform.

Essentially, the jack-head consists of a more or less elliptically shaped member 1 having a forward upturned, elevated end portion 2, and a lower opposite end portion 3. The body section 35 of the head 1 is preferably made of metal and may be bent from a sheet, machined, or cast. The size and strength of the head is varied according to the weight it must support. Referring to Fig. 1, it will be seen that the head possesses a symmetrically curved face which terminates at a considerably higher height than the base portion of the head. This face 4 is in the nature of a cam surface, so that all portions thereof are arcuate and possess no angular or straight surfaces. A forwardly extending symmetrically shaped nose 5 may be provided. The middle section of the head 6 is substantially flat and forms the base for the head member to be applied to the elevating rod A of a vehicle jack. The lower rearward extension 3 of the head terminates slightly above the horizontal plane of the base portion 6.

Continuously formed around the upper edge of the head 1 is an upstanding edge 7, and, as clearly shown in the several views of the draw-

ing, the exterior areas and edges of the head present only curved surfaces. The head may be affixed to the lifting rod A of a jack by means of a screw bolt 8, or the end of the lifting rod A may be reduced in diameter, passed through an opening in the head and either swaged or welded, as shown in Fig. 3. In Fig. 2 the head is rigidly bolted to a rotating screw-type lifting rod A, while in Fig. 4 a swivel screw is used, so that the head may turn on the non-rotating toothed lifting rod A. In all forms of attachment, however, the head is mounted off-center of the lifting rod A.

A transverse upstanding lug 9 is suitably formed in the lower portion of the inner face of the arcuate section 2, for the purpose of holding a drift pin 10, upon which is pivoted a hinged platform or weight supporting member 11. This pivoted platform is formed with an interior cavity or bore 12 in which is fitted a coil spring 13 bearing against a tubular plug 14. The upstanding lug 9 is formed with oblique front and vertical rear faces, against which the plug 14 is urged by the spring 13. As illustrated in Fig. 2 the platform 11 normally lies in upward pivoted position and is encompassed within the arcuately formed portion 2. The plug 14 bearing against the outer face of the lug 9 holds it in snug position. Fig. 3 illustrates the platform 11 after it has been pivoted downwardly and rests directly over the elevating rod A of the jack, the plug 14 bearing on the inner straight face of the lug 9 in this position. The base portion 6 of the head and the under-face of the pivoted platform 11 are preferably flat, so that all the weight applied on the upper surface of the platform is equally distributed and no part of the axle, etc., contacts with the raised edge 7.

Fig. 6 is a modified form of head, wherein the pivoted platform 20 is provided with an extension 21 which is bent around a drift pin 22. This pin is set transversely in an opening 23 formed in the middle portion of the plate and permits the platform 20 to be pivoted thereabout and lie in a similar operative position to the platform shown in Fig. 2. A latch pin 24 is carried through an opening in the upper portion of the high side of the head, and is retained in position by flat spring 25 which is secured in a slot 26 in the outer face of the high end portion. A cooperating slot 27 receives the latch pin 24 to hold the platform in elevated position. When it is desired to lower the platform, it is only necessary to disengage the latch pin, whereupon the

platform is pivoted downwardly to lie directly over the lifting rod.

In operation the hinged platform is unlatched and pivoted over the lifting rod A and the jack, with the upstanding or high edge of the head forward, moved into contact with the axle or other part of the automobile. The high portion of the head upon contacting the axle or spring, etc., and because of its symmetrical arcuate exterior, is swivelled or swung around on the jack lifting rod, so that the platform is directly under the axle or other point of contact, where the vehicle will be supported when raised. As the lifting rod of the jack is elevated, the weight of the car is firmly supported on the roughened upper surface of the platform and the entire weight is distributed evenly over the platform, and, consequently, through the elevating rod to the jack-base. The exterior contour of the head is such that rotary self-centering movement is imparted to the head at no matter what degree of angle it is presented to the axle. If, for any reason, the jack-head becomes turned around or swivels while being placed under the car so that the high portion, instead of being forward, is towards the rear, the high offset will still strike the axle, etc., and arrest it, and upon elevation of the rod, support the weight of the car on the platform.

30. What I claim is:

1. A self-centering head for vehicle jacks including a horizontal base section, an integral upstanding extension on one end of said base section, and a pivoted weight distributing platform normally lying against said upstanding exten-

sion and adapted to pivot over and contact with said base portion.

2. A self-centering head for vehicle jacks including a substantially horizontal base portion, an upwardly extending extension therefor integrally formed on one end thereof, and an auxiliary pivoted weight supporting platform normally lying against said extension and adapted to pivot over against the horizontal base portion. 5

3. A self-centering head for jacks including a substantially horizontal base portion, an upwardly extending concaved extension on one end of said base portion, a weight distributing platform pivoted to the said base portion and adapted to contact therewith when weight is 10 being supported by said head and to be retained in said concave extension when not supporting weight. 15

4. A self-centering and self-locating head for vehicle jacks including a horizontally disposed base plate having a flat central portion and a concave elevated end portion, a weight distributing platform pivoted to said base plate and normally lying within the concaved end portion while adapted to pivot over and overlie the flat 20 central portion. 25

5. A self-centering head for vehicle jacks including a substantially horizontally disposed base plate having a flat central portion and an upwardly extending end portion, a platform member pivotally attached adjacent the central portion of the said base plate and adapted to be held in contact with either said central portion or said end portion. 30
